UNITED STATES PATENT OFFICE.

EDWARD A. RUSSELL, OF CHICAGO, AND PAUL E. PARKS, OF OAK PARK, ILLINOIS, AS
SIGNORS TO VAPOR CAR HEATING COMPANY, INC., OF CHICAGO, ILLINOIS, A COR-
PORATION OF NEW YORK.

LIMIT SWITCH FOR VALVE-OPERATING MECHANISM.

Application filed September 5, 1925. Serial No. 54,799.

This invention relates to improvements in an automatic valve-operating mechanism for a car-heating system, said mechanism including a new and improved limit-switch for automatically breaking the operating circuits to a pair of valve operating motors, after each motor has functioned to move the valve to either an open or closed position. In a car-heating system, such for example as shown in the patent to Russell 1,440,701, granted January 2, 1923, a control valve is provided having a rotary part which is to be swung at intervals from one position to another to turn on or shut off the steam supply to the car radiators. These movements of the valve member are accomplished automatically by the thermally controlled mechanism whereby when the car atmosphere becomes heated to the desired temperature the valve is moved by an electric motor or solenoid to its closed position. When the temperature falls below the desired point, the valve is swung back by another motor to open position, to again admit heating medium to the radiators. A limit-switch is provided in the operating circuits for the motors, this switch being operated by the movement of the valve-operating lever to break the circuit to the operating motor after it has accomplished the desired valve movement. This invention relates more particularly to a new and improved switch for performing this function.

One object of the invention is to provide a switch of this type comprising a pivoted contact member that is adapted to be quickly snapped from engagement with one fixed contact into engagement with another similar fixed contact. The movement of the valve-operating lever from one position to another serves to compress a spring, the spring being released as the lever approaches the end of its movement, to quickly snap the movable contact member from one position to another, thus breaking the circuit to the motor, which has just moved the valve operating lever. The movable contact member is left in position to complete the circuit to the other motor, whereby the next

valve-operating movement may be performed. Another object is to provide an improved electric terminal connector, for joining the ends of the leads between the switch and the motors, and for simultaneously holding the switch mechanism in position adjacent the motors.

Other objects and advantages of this invention will be apparent from the following detailed description of one approved form of the mechanism involving the principles of this invention.

In the accompanying drawings:

Fig. 1 is a plan view of the assembled valve-operating mechanism, including the solenoids and the limit-switch. 65

Fig. 2 is a section, on a somewhat larger scale, taken substantially on the line 2—2 of Fig. 1.

Fig. 3 is a section taken substantially on the line 3—3 of Fig. 2. 70

Fig. 4 is an enlarged section through one of the terminal connectors, the view being taken substantially on the line 4—4 of Fig. 1.

Fig. 5 is a section taken substantially on the line 5—5 of Fig. 4. 75

Fig. 6 is a perspective view of one of the connector blocks.

Fig. 7 is a perspective view of one of the slidable binding posts.

Fig. 8 is a diagrammatic view and wiring 80 diagram, showing the valve and its operating connections.

Referring first to the diagram shown in Fig. 8, 1 is the control valve, comprising a rotatable part 2 (shown in dotted lines), 85 from which projects an operating shaft 3, to which is attached the lever 4 for swinging the valve member from one position to another. When the valve is in the position shown, steam or other heating medium will flow in from the train pipe through pipe 5, then through the valve and pipe 6 to the radiators from which it returns to the valve through pipes 7 and 8 and out through pipe 9 to the vapor-regulator. When lever 4 is 90 swung over to a corresponding position at the other side of the vertical, rotary member 2 will be moved to cut off the flow of

steam to the radiators, putting inlet pipe 5 in direct connection with outlet pipe 9. All of the above is more clearly disclosed in greater detail in the Russell patent referred 5 to hereinabove.

The valve-operating lever 4 is moved from one position to the other by means of a pair of electric motors A and B, and C is the limit-switch for automatically breaking the 10 circuits to the two motors A and B, after each has functioned to move the valve. As here shown, the motors A and B are in the form of a pair of solenoids, the coils 10 and 11 of which surround the ends of a common 15 core 12, which is centrally connected at 13 to one end of operating lever 4. The two negative leads 14 and 15 from the thermally operated control mechanism are connected with one end of coils 10 and 11 respectively, 20 and the other ends of these coils are connected through wires 16 and 17 with a pair of fixed contact members 18 and 19 in limit switch C. The positive lead 20 from the control mechanism is connected to an oscillating member 21, carrying contacts 22 and 23 adapted to alternately engage with the fixed contacts 18 and 19. As already stated, with the parts in the position shown in Fig. 8, the valve 1 is open and steam is flowing 25 to the radiators. When the car temperature has reached the desired maximum, the thermally operated control mechanism (not here shown but disclosed in the Russell patent hereinabove referred to), will close a circuit 30 through solenoid A, the portion of this circuit here shown comprising positive lead 20, swinging contact member 21, contact 22, fixed contact 18, wire 16, coil 10, and negative lead 14. The energization of solenoid 35 A will draw in the core 12, thus throwing lever 4 over to a corresponding position at the other side of the vertical and closing valve 1. As lever 4 nears the end of this movement it will, through delayed action 40 mechanism in limit switch C, as hereinafter described, snap over the swinging member 21 to separate the contacts 18 and 22, thus breaking the circuit to motor A. At the same time, this portion of an operating circuit 45 for motor B will be completed as follows: positive lead 20, swinging member 21, movable contact 23, fixed contact 19, wire 17, coil 11, and negative lead 15. When the car temperature has fallen below the desired 50 point, the thermally operated control mechanism will complete a circuit through leads 20 and 15, whereby motor B will be energized to throw the valve back to the position shown in Fig. 8. At the completion of this movement, swinging member 21 will be snapped back to the position shown in Fig. 8, breaking the circuit to operating motor B by separating the contacts 19 and 23.

Having now described in a general way 55 the operation and purpose of this valve-

operating mechanism and limit-switch, we will now refer to Figs. 1 to 7 for a more detailed disclosure of the mechanism. The solenoids A and B are suitably supported within a casing 24, from one side of which projects a free end 25 of operating lever 4, by means of which the valve may be manually operated if necessary. This end of the operating lever may project over a suitably marked indicating plate 26 whereby the position of the valve may be easily noted. It will be seen that this arm of the operating lever is engaged between a pair of operating collars 13 on the core 12 of the solenoids, whereby the lever is automatically operated 70 to swing the valve shaft 3.

Blocks of insulating material 27 and 28 are secured near the adjacent ends of solenoid bodies A and B in any suitable manner, as by screws passing through these blocks into the casing of the solenoids. Each block (for example the block 27 as shown in Figs. 4, 5 and 6), has a pair of holes or passages 29 and 29^a into which project the terminals 30 and 31 of the solenoid coil. These passages 29 and 29^a partially intersect another pair of passages 32 and 33 in the block, in which are slidably mounted the metallic binding posts 34 and 35. These posts have cut-away 80 grooves or passages 36 and 37 adapted to register with the passages 29 and 29^a and engage about the terminals 30 and 31. Preferably the passages 32 and 33 and the interfitting posts 34 and 35 are of square or other irregular cross section to prevent turning 85 movement of the posts in the passages and insure correct registration of grooves 36 and 37 with the passages 29 and 29^a. Binding screws 38 and 39 engage in the upper ends 90 of the posts 34 and 35. One end of the lead wire 14 is engaged beneath the binding screw 39 and the screw is tightened. This will draw up the post 35 to tightly clamp 95 this post against the terminal 31 and insure a good electrical connection at this point, and will simultaneously draw the screw 39 down against the lead 14 to make electrical contact at this point.

The limit switch C comprises a base plate 100 40 of insulating material, on the back of which are mounted two metallic brackets 41 and 42 having projecting flanges 43 and 44 adapted to overlie the respective insulating blocks 27 and 28. These flanges 43 and 44 are slotted to receive the binding screws 38, by means of which the switch C is secured to the insulating blocks. These brackets 41 and 42 also perform the functions of the leads 16 and 17 of Fig. 8, so that it will be 110 seen that the tightening of screws 38 serves to simultaneously engage the posts 34 with the coil terminals 30, to make electrical connections with the metallic brackets 41 and 42, and also to secure the limit switch C in 115 assembled relation with the solenoids.

On the opposite side of insulating base plate 40 are mounted the contact plates 45 and 46, by means of screws 47 and 48 projecting through base plate 40 into brackets 41 and 42, whereby the plates 45 and 46 are electrically connected with the respective brackets. Plates 45 carries a fixed contact member 18 and plate 46 supports a similar fixed contact 19. A third contact plate 51 is secured on the insulating base 40 and has a bracket extension 52 to which the positive lead 20 is electrically connected. On the other end of plate 51 is mounted a metallic loop 53, between the sides of which are pivoted the moving parts of the switch. The movable contact member 21 is of an inverted T-shape, the arms of the head 54 of the T carrying the contacts 22 and 23, adapted to engage respectively with the fixed contacts 18 and 19. The body portion of the T is U-shaped, with the extremities of its legs 57 pivoted on a pin 58 mounted in the sides of the loop 53. An operating lever 59 is intermediately pivoted on another pin 60 mounted in loop 53, there being tubular spacers 61 mounted about pin 60 between the sides of lever 59 and the respective sides of the loop. The longer arm of lever 59 is engaged by the forked end 62 of the valve-operating lever 4.

This forked end 62 of lever 4 is formed to hold a block of insulating material 63, held in place by rivet 64 and notched at 65 to engage about the head of lever 59. The shorter arm of lever 59 is slotted at 66 to permit swinging movement about the fixed pin 58, and its extreme end is forked at 67 to engage a pin 68 in the end of a link 69. The other end of this link projects through an opening 70 in the head 54 of the swinging contact member. A compression spring 71 is confined between the head 54 and a flange 72 on link 66.

It will be seen that as the valve operating lever 4 is moved from one side to the other about its pivot 3, it will correspondingly swing the operating lever 59 about its pivot 60. This movement of lever 59 will swing the link 69 to bring it into substantial alignment with the lever, thus compressing the spring 71. The parts will not pass beyond this position of alignment until the movement of lever 59 is nearly completed. As soon as pin 68 is swung slightly beyond the line connecting pivot 60 with the aperture 70 in head 54, the spring 71 will suddenly expand and snap the movable contact member over to its opposite position with contact 23 against contact 19, thus breaking the circuit through contacts 18 and 22. Obviously the same movements will take place in a reverse direction upon the return movement of valve operating lever 4. It will be noted that while the movements of the valve operating lever 4 may be comparatively slow

and steady, the movement of the movable contact member 21 will be sudden and will take place only after the valve operating movements have been practically completed. Obviously, the motor circuits as described in connection with Fig. 8, will flow from positive lead 20 through the plate 51 and the movable parts of the switch to the fixed contact 18 or 19, with which movable contact member 21 is then engaged. As illustrated in the drawing, the current will flow from lead 20 through plate 51, legs 57, head 54, contact 22, contact 18, plate 45, screw 47, bracket 41, binding screw 38, binding post 34, terminal 30, coil 10, terminal 31, binding post 35, binding screw 39, and lead wire 14 to the thermally operated controlling mechanism.

It will be seen that this new limit switch is compact and easily assembled with the operating solenoids, and that a minimum number of operating connections are involved. The new connector blocks, illustrated in Figs. 4 to 7 inclusive, provide a convenient means for mounting the limit switch on the solenoids, and at the same time insure tight electrical connections between the switch members and the coil-terminals. The movable parts of the limit-switch may be enclosed in a removable casing 73, which snaps in place on the insulating base plate 40, and the entire valve-operating assembly may be inclosed in a casing 24, hereinabove referred to.

We claim:

1. The combination with a valve comprising a rotary member, an operating lever connected with the rotary member, and a pair of solenoids for alternately swinging the lever in one direction or the other, of a limit switch comprising an insulating base, three separate electric terminal plates mounted on said base, a pair of similar fixed contacts carried by two of the plates each of these plates also being electrically connected with one terminal of one of the solenoids, an oscillatable member pivoted on the third plate and carrying contact members to alternately engage with the fixed contacts as the member is oscillated, a second operating lever pivoted on the base and connected with the first mentioned operating lever, and a spring mounted between portions of the second operating lever and oscillatable member whereby the spring will be stressed as the lever is moved to a position of alignment therewith, and will thereafter operate to snap the member from one fixed contact to the other.

2. The combination with a valve comprising a rotary member, an operating lever connected with the rotary member, and a pair of solenoids for alternately swinging the lever in one direction or the other, of a limit switch comprising an insulating base,

three separate electric terminal plates mounted on said base, a pair of similar fixed contacts carried by two of the plates each of these plates also being electrically connected with one terminal of one of the solenoids, an oscillatable member pivoted on the third plate and carrying contact members to alternately engage with the fixed contacts as the member is oscillated, a second operating lever pivoted on the base and connected with the first mentioned operating lever, a link pivotally connected at one end with the second operating lever and slidably engaged at its other end with the free end of the oscillatable member, and a spring mounted on the link and adapted to be compressed as the operating lever and link are swung to a position of alignment.

3. The combination with a valve comprising a rotary member, an operating lever connected with the rotary member, and a pair of solenoids for alternately swinging the lever in one direction or the other, of a limit switch comprising an insulating base, three separate electric terminal plates mounted on the base, a pair of similar fixed contacts carried by two of the plates each of these plates also being electrically connected with one terminal of one of the solenoids, a T-shaped member having its leg portion pivoted on the third plate and carrying a pair of contacts, one on each arm of the T-head, adapted to engage alternately with the fixed contacts, a second operating lever connected with the first operating lever and intermediately pivoted on the base with one end overlying the pivoted leg of the member, and a compression spring mounted between this end of the lever and the head of the T whereby the spring will be compressed as the lever is swung into alignment therewith and will thereafter snap the member from a position against one fixed contact to a similar position against the other fixed contact.

4. In combination with a valve comprising a rotary member, an operating lever connected with the rotary member, and a pair of solenoids for alternately swinging the lever in one direction or the other, a pair of spaced fixed contacts each connected with a terminal of one of the solenoids, a swinging contact member adapted to engage alternately with the fixed contacts, one power lead for either solenoid being connected with this member, and connections comprising a spring between the operating lever and the swinging member whereby as the lever is moved by one solenoid to operate the valve the spring will be compressed and will snap the swinging contact member from one fixed contact to the other as the operating lever nears the limit of its movement, thus breaking the circuit through this solenoid.

5. In combination with a valve comprising

a rotary member, an operating lever connected with the rotary member, and a pair of solenoids for alternately swinging the lever in one direction or the other, a pair of spaced fixed contacts each connected with a terminal of one of the solenoids, a movable contact member adapted to alternately engage with the fixed contacts, one power lead for either solenoid being connected with this movable member, and connections between the valve operating lever and the movable member comprising a spring which is compressed as the lever is moved by one solenoid to operate the valve, the spring snapping the movable member from one fixed contact to the other as the lever nears the limit of its movement, thus breaking the circuit through the operating solenoid.

6. In combination with a valve operating lever, a pair of solenoids for alternately swinging the lever in one direction or the other, an insulating base plate, a pair of metallic supporting brackets mounted on one side of the base plate and secured one on each solenoid, and each electrically connected with one terminal of the respective solenoid, a pair of fixed contact plates mounted on the opposite side of the plate, and electrically connected with the respective brackets, a third contact plate on the base, a movable contact member mounted on the plate and adapted to alternately engage with the fixed contacts, and connections between the movable contact member and the valve operating lever.

7. The combination with a valve operating lever, and a pair of solenoids for alternately swinging the lever in one direction or the other, of a block of insulating material mounted on each solenoid, there being two intersecting passages in the block into one of which extends a terminal of the solenoid, a metallic post slidably fitting within the other passage and having a cutaway portion to register with the first passage, a switch mechanism comprising a pair of fixed contacts, a movable contact, the movable contact being operatively connected with the valve-operating lever, and a pair of supporting brackets electrically connected with the fixed contacts, and a binding screw engaging the exposed end of each post and adapted to simultaneously secure a bracket to the block and draw the post into engagement with the solenoid terminal.

8. The combination with a valve operating lever, a solenoid for operating the lever in one direction, and means for operating the lever in the other direction, of a block of insulating material mounted on the solenoid the block having two pairs of intersecting passages, the terminals of the solenoid coil projecting into one passage of each pair, metallic posts slidably fitted in the other passages and having cutaway portions to

register with the first passages, a switch mechanism comprising a movable member operatively connected with the valve-operating lever and a supporting bracket forming one terminal of the switch, and binding screws engaging the posts and drawing them into engagement with the solenoid terminals, one of these screws being also adapted to secure the supporting bracket to the block, and the other screw also serving as a binding post for the other terminal of the solenoid.
